(57) **CLAIM**

We claim, The ornamental design for a portable urine collection station, as shown and described.

DESCRIPTION

FIG. 1 is a front view of a portable urine collection station of my new design,

FIG. 2 is a back view thereof,

FIG. 3 is a left side view thereof, the right side being a mirror image,

FIG. 4 is a perspective view thereof,

FIG. 5 is a top view thereof; and,

FIG. 6 is a bottom view thereof.

The dashed lines shown in the Figures are environmental structure that form no part of the claimed design.

1 Claim, 2 Drawing Sheets
